UNITED STATES PATENT OFFICE.

JACOB J. BUSENBENZ, OF CHICAGO, ILLINOIS, ASSIGNOR TO THE UNITED STATES AUTOMATIC PERFUMING COMPANY, OF SAME PLACE.

VENDING APPARATUS.

SPECIFICATION forming part of Letters Patent No. 430,464, dated June 17, 1890.

Application filed February 20, 1890. Serial No. 341,132. (No model.)

To all whom it may concern:

Be it known that I, JACOB J. BUSENBENZ, a citizen of the United States, residing at Chicago, in the county of Cook and State of Illinois, have invented a new and useful Improvement 5 in Vending Apparatus, of which the following is a specification.

My invention relates to an improvement in the class of vending apparatus requiring a 10 coin representing the price of the purchase to be inserted into it to permit the delivery mechanism to be controlled to produce the delivery of the article so purchased.

The object of my improvement is to provide 15 an apparatus of the class referred to especially for use in selling liquid perfumery, and which shall operate by means of pneumatic pressure to effect the delivery and involve a simply constructed and durable and 20 reliably operative delivery mechanism.

My invention consists in the general construction of my improved apparatus; and it also consists in details of construction and combinations of parts, hereinafter set forth 25 and claimed.

In the accompanying drawings, Figure 1 represents my improved vending apparatus by a broken view in sectional side elevation, and Fig. 2 is a perspective view showing the 30 sign detail.

A is the chamber for containing the supply of the article to be sold and the delivery mechanism hereinafter described, and the chamber A should be provided with a hinged 35 cover *r*, and be supported on a hollow standard A', containing a coin-receptacle B, accessible through a door *q* in a side of the standard.

In the chamber A is a receptacle C for the article to be sold and delivered by the apparatus 40 and containing a float *p* on the end of a rod *p'*, extending through the top of the receptacle, the vertical play of the float being limited by stops *o* and *o'*, respectively, outside and inside the receptacle on the rod *p'*. The 45 rod *p'* is pivotally connected at its upper end with a lever *n*, fulcrumed at *x* and extending toward an opening *m* in the front side of the chamber, where it carries a sign *l*, thus located just behind the opening, and which 50 should have marked horizontally across its upper portion the name of the contents of the

receptacle C, (kind of perfume,) and across its lower portion the word "out," or some other indication of the empty or practically empty condition of the receptacle. As will be seen 55 from the description of the float mechanism, when the receptacle C is empty, the consequent low position of the float raises the lower portion of the sign to view at the opening *m*, and if the receptacle contains a material 60 quantity of the liquid the position of the float will be sufficiently elevated to lower the upper portion of the sign into coincidence with the said opening.

D is a tube of flexible material (such as 65 rubber) extending from near the base of the receptacle C through a bearing *k* toward the front side of the chamber A, wherein it is connected with the rear end of a nozzle E, extending through such side of the chamber, 70 and which preferably terminates in a spraying-bulb *i*.

F is a lever pivoted at its center, and thereby supported to tend to extend perpendicularly to a bracket *h*, through the medium of 75 a shaft *h'*, supported in the bracket, and near the opposite ends of the lever F, extending from one side thereof, are the studs *g* and *g'*, engaging, respectively, with fingers *f* and *f'*, which I term "valve-fingers," at elongated 80 slots *x'* in the rear ends of the latter, the fingers being supported in horizontal position in a bearing *k'*, there to coincide with the tube D, and controlled by springs *f²* and *f³*, confined between stops *x³* and the inner surface 85 of the front wall of the chamber, into sockets in which the spindle ends of the valve-fingers extend, as shown.

G is a tube supported from one end against the inner surface of the front side of the 90 chamber A, to extend horizontally therein, as shown, and provided in its base with an opening *e*, from which a conducting-tube *e'* leads into the standard A', through the base of the chamber A. A chute H communicates at its 95 lower end with the tube G at an opening *e²* in its upper side, near a partition *e³* and slightly back of the opening *e* in the under side thereof, and at its upper end the chute leads to a slot (not shown, but like slots in 100 other devices of the kind to which my improvement relates) provided to extend horizontally

through the front side of the chamber at s , as indicated in the drawings.

Within the tube G , and normally in position therein to cover the opening e , but to extend beyond the opening e^2 , is a shorter sliding tube G' , open at or provided with an opening in its end adjacent to the partition e^3 , and preferably closed at its opposite end, between which and the inner end of the tube G , which is provided with an inwardly-opening check-valve t , is confined a spring u . A plunger-rod d , having a suitable knob d' at its outer end, extends through the front side of the chamber into the tube G , wherein it is reduced in diameter, as shown, and controlled by a spring t' , confined between the side of the chamber A and partition e^3 , through which latter the plunger-rod extends. An arm h^2 is connected from near its upper end with an arm of a bent connecting-bar h^3 , the other arm of which extends through a slot in the base of the tube G into connection with the plunger-rod d . The lower end of the arm h^2 is secured to the shaft h' .

Above the plunger-rod d a plunger-rod c , having a knob c' at its outer end, extends through the front side of the chamber A and is pivotally connected at a slot c^2 , near its innermost end, with a dog or catch w , pivotally supported on the upper side of the tube G and normally extending at its hooked end into a slot w' in the said tube near the innermost end of the sliding tube G' , when the latter is in its normal position illustrated.

The plunger-rod c is provided just inside the chamber A with a horizontally-disposed cross-bar b , preferably tapering, as indicated, on its side adjacent to the front side of the chamber, and against the opposite side of which bears a spring b' , the cross-bar thus forming a spring-clamp.

Near the innermost end in the upper side of the tube G is an opening v , covered by an outwardly-opening check-valve v' , and around which is a bulb v^2 , forming a coupling for one end of an air-pipe a , which extends thence across the tapering side of the clamp b , between the latter and inner surface of the front side of the chamber A , and leads at its opposite end through the bearing k into the tube D just above the plane of the valve f .

The operation is as follows, the parts being normally in the relative positions in which they are illustrated: By dropping a coin I —as a penny—through the slot into the chute H it falls therein through the opening e^2 into the tube G , between the open end of the sliding tube G' and the partition e^3 , and being of greater diameter than the opening in the inner sliding tube it covers the open end thereof, thus forming a bearing for the inner end of the spring plunger-rod d . The sliding tube is then a piston to force air admitted into the tube G through the check-valve t , under pressure into the pipe a . This is accomplished by pressing the spring plunger-rod d against the coin I , whereby the piston

G' is moved against the spring u toward the inner end of the tube G , and compresses the air in the latter into the pipe a , wherein it is confined between the point of closure at the clamp b and the check-valve v' until released in the manner hereinafter described. The pressure, which is exerted to the extent of the inward play of the plunger-rod d , brings the open end of the piston G' beyond the pivotal hook w , which then falls into engagement with such end and retains the tube G' against being forced back by the resilience of the spring u when the plunger-rod d is released and returned by the action of its spring t' . With the piston G' advanced and held in the manner described the coin I is in line with the farther edge of the opening e , so that when the plunger-rod d is released and recedes, the coin being thereby freed from the pressure against it falls through the conduit e' into the coin-receptacle B . The purpose of retaining the sliding tube G' in its advanced position, as described, is to prevent coaction of the two springs u and t' in expanding, when the plunger-rod d is released, from continuing to hold the coin and thus preventing it from dropping. Normally the pivotal lever F is in position, as illustrated, to advance the lower valve-finger f against the pipe D , to close it below the communication therewith of the air-pipe a , and retract the upper valve-finger f' . Thus the tube D is normally devoid of contents (perfume) from above the point of normal closure of the tube at the finger f . When the plunger-rod d is pressed inward, with the result described, it also moves forward with it, through the bent connecting-bar h^3 , the arm h^2 . This forward movement of the arm h^2 moves the upper end of the lever F , through the medium of the shaft h' , in the same direction, and the lower end in the opposite direction. It is to be noted that the spring t' , through the arm h^2 and lever F , normally maintains the upper valve-finger f' in the retracted position shown, against the resistance of the spring f^3 , whereby the stud g is normally against the forward end of the longitudinal slot x' of the lower valve-finger, while the stud g is for the same reason normally against the rear end of the longitudinal slot x' of the upper valve-finger, and both valve-fingers f and f' are immediately controlled by the resilience of their respective springs f^2 and f^3 . Thus when the plunger-rod d is pressed inward, owing to the lost motion of the studs g and g' in the slots x' , the upper valve-finger advances by the resilience of its spring f^2 to compress the pipe D before the lower valve-finger is disengaged from it. When, however, the stud g reaches the rear end of the slot x' engaging it, its further movement, under the continued pressure upon the plunger-rod d , retracts the lower valve-finger f , thereby opening the pipe D below the valve-finger f' to permit the compressed air, when released, as hereinafter described, to blow the perfume ahead of it in

the pipe D out through the nozzle E, where it may be caught by the purchaser, as by applying a handkerchief or other article to be perfumed to the spraying-bulb i. The release 5 of the air confined under pressure in the tube a is produced after the rod d has been manipulated by inward pressure upon the plunger-rod c, which disengages the spring-clamp b from the tube and permits the air confined 10 therein to expand and force out the perfume in the pipe D above the closure at the valve-finger f, and furthermore disengages the dog w, permitting the spring t to return the sliding tube G' to its normal position. 15 Of course, as will be understood, the results described as attending the inward pressure of the plunger-rods d and c are practically instantaneous. Upon releasing the rod c the spring b' returns it with the clamp b to their 20 normal positions, and on releasing the rod d its return by the spring t' brings back the valve-fingers f and f' to their normal relative positions, the lower valve-finger f then remaining stationary in its advanced position 25 until the upper one has been advanced, owing to the lost motion of the studs in the slots x'. It will thus be seen that the coin I introduced into the tube G is the primarily essential medium for permitting the delivery to be 30 accomplished, since without it the plunger-rod d when pressed inward enters the tube G' without moving the latter, thus without compressing air into the pipe a for discharging the perfume admitted into the tube D. 35 The somewhat intricate nature of the mechanism employed in my improved apparatus renders the foregoing detailed description of the parts necessary to permit the operation to be clearly comprehended. I do not, however, 40 wish to be understood as intending to limit myself to the exact details shown and described, as these may be variously modified without thereby departing from my invention, which I consider to consist, broadly stated, 45 in the general construction of the tubes G and G', whereby a coin introduced in the manner described will cause the plunger d, by pressure upon it, to produce a supply of compressed air sufficient to deliver, when released, 50 the article for the purchase of which the coin is so inserted. In the same apparatus the number of receptacles C may be multiplied to any desired number practicable, and each connected with a separate delivery 55 to be actuated by the single plunger d and tube G, with its immediately attending parts. This, however, is too obvious to require detailed illustration and description.

What I claim as new, and desire to secure 60 by Letters Patent, is—

1. In a coin-operated vending apparatus, the combination, with a chamber A, of a tube G, containing a spring-controlled hollow piston G', open at one end, a plunger-rod d, extending 65 into the said tube, a chute H, communicating at its upper end with the coin-insertion slot s and at its opposite end with

the tube G, near the open end of the hollow piston therein, an outlet e in the tube for the coin, a receptacle C, having an outlet-pipe D 70 leading outside the chamber, and an air-pipe a leading from the tube G and controllably communicating with the pipe D, substantially as and for the purpose set forth.

2. In a coin-operated vending apparatus, 75 the combination, with a chamber A, of a tube G, containing a spring-controlled hollow piston G', open at one end, an inwardly-opening check-valve t and an outwardly-opening check-valve v' in the inner end portion of 80 the tube G, a spring plunger-rod d, extending into the said tube through a suitable bearing e³ therein, a chute H, communicating at its upper end with the coin-insertion slots and at its opposite end with the tube 85 G, near the open end of the hollow piston therein, an outlet e in the tube for the coin, a receptacle C, having an outlet-pipe D, leading outside the chamber, and an air-pipe a, leading from the tube at the check-valve v, 90 and controllably communicating with the pipe D, substantially as and for the purpose set forth.

3. In a coin-operated vending apparatus, 95 the combination, with a chamber A, of a tube G, containing a spring-controlled hollow piston G', open at one end, a plunger-rod d, extending into the said tube, a chute H, communicating at its upper end with the coin-insertion slot s and at its opposite end with 100 the tube G, near the open end of the hollow piston therein, an outlet e in the tube for the coin, a receptacle C, having an outlet-pipe D leading outside the chamber, spring-controlled valve-fingers f and f', one above the 105 other, in the plane of the pipe D, an air-pipe a, leading from the tube G into the pipe D near the lower valve-finger f', and a spring-controlled plunger-rod c, having a clamp b engaging the pipe a, substantially as and for 110 the purpose set forth.

4. In a coin-operated vending apparatus, 115 the combination, with a chamber A, having an opening m, of a receptacle C, containing a float p, having a rod p' extending through the receptacle and provided with stops o and o', respectively, without and within the receptacle, and a sign l at the said opening and connected with the said rod, substantially as and for the purpose set forth.

5. In a coin-operated vending apparatus, 120 the combination, with a chamber A, of a tube G, provided with the valves t and v', and containing a spring-controlled hollow piston G', open at one end, a spring plunger-rod d, 125 extending into said tube, a chute H, communicating at its upper end with the coin-insertion slot s and at its opposite end with the tube G, near the open end of the hollow piston therein, an outlet e in the tube for the 130 coin, a receptacle C, having an outlet-pipe D, leading to a nozzle E in one side of the chamber, a lever F, provided with studs g and g' near its opposite ends, spring-con-

trolled valve-fingers *f* and *f'*, having slots *x*' engaged by the said studs and supported one above the other in the plane of the pipe *D*, a spring-controlled plunger-rod *c*, having a clamp *C* and engaging at its inner end with a pivotal catch *w* for the hollow piston *G'*, an arm *h*', connected from one end with the plunger-rod *d* and at its opposite end with the shaft *h*', and an air-pipe *a*, leading from the

tube *G* at the valve *v'*, through the clamp *b* into the pipe *D*, near the lower valve-finger *f*, the whole being constructed and arranged to operate substantially as described.

JACOB J. BUSENBENZ.
